UNITED STATES PATENT OFFICE.

AXEL GOTTFRID LUNDQVIST, OF OAKLAND, CALIFORNIA.

TROUSERS PROTECTOR.

1,404,987.

Specification of Letters Patent. Patented Jan. 31, 1922.

Application filed April 16, 1920. Serial No. 374,413.

To all whom it may concern:

Be it known that I, AXEL GOTTFRID LUNDQVIST, a citizen of Sweden, residing at Oakland, in the county of Alameda and State of California, have invented certain new and useful Improvements in Trouzers Protectors, of which the following is a specification.

This invention relates to improvements in wearing apparel and more particularly to trousers seat protectors and its object is to provide means for protecting the seats and upper leg portions of trousers from wear. The protector can be almost instantly put on or taken off and is adapted primarily for use by those of sedentary occupations.

With the foregoing and other objects in view the invention consists in the combination and arrangement of parts to be herein-after fully described, pointed out in the appended claim and illustrated in the accompanying drawing which forms a part of this specification and in which—

Fig. 1 is a view of my trousers protector in front elevation.

Fig. 2 is a rear view of the same.

Like reference characters denote corresponding parts in both views.

My trousers protector is preferably made of a single piece of material comprising the body portion 1 having the lower extensions 2, 3 arranged upon opposite sides of the crotch 4. The body portion 1 is adapted to cover the seat of the trousers to which it is to be applied or secured and the extensions to cover the upper portions of the trousers legs upon the trousers seat side. The body portion is formed with the elongated slits

5 through which access to the trousers hip pockets may be had. The lateral edges of the body portion and of the leg portions are turned back and sewed to the garment proper forming the seams 6.

To the upper corners of the body portion 1 I secure the elastic supports 7 adapted to pass about the trousers at about the waist band and provided with the loop terminations 8 adapted to be secured to a trousers button to support the garment in position. Leg straps 9 are secured to the adjacent seams of the leg portions and are adapted to pass about the trousers legs and to engage with the snap heads or buttons 11 secured upon the leg portions to support the same in position.

What is claimed is:—

In a trousers protector comprising a single piece of material, a body portion formed with elongated slits and adapted to cover the trousers seat, leg portions extending from said body portion, flexible supporting bands for said leg portions, and flexible supporting means for said body portion adapted for engagement with buttons of the trousers whereby said elongated slits may be positioned and retained in alignment with the mouths of the hip pockets in the trousers.

In testimony that I claim the foregoing as my own I have hereto affixed my signature in the presence of two subscribing witnesses.

AXEL GOTTFRID LUNDQVIST.
